CLAIM

The ornamental design for a vehicle decklid, as shown and described.

DESCRIPTION

FIG. 1 is a perspective view of the vehicle decklid; FIG. 2 is a front view thereof; FIG. 3 is a left side elevation view thereof (where the right side elevation view is omitted since the right side elevation view is identical to the left side elevation view); and, FIG. 4 is a top plan view thereof.

The broken lines form no part of the claimed design. All surfaces surrounding the broken lines, both inside and out, form part of the claimed design.
